United States Patent Office.

ALONZO WARREN, OF BOSTON, MASSACHUSETTS.

Letters Patent No. 96,853, dated November 16, 1869.

IMPROVEMENT IN WATER-WHEELS.

The Schedule referred to in these Letters Patent and making part of the same

To all whom it may concern:

Be it known that I, ALONZO WARREN, of Boston, in the county of Suffolk, and State of Massachusetts, have invented certain Improvements in Turbine Water-Wheels, of which the following is a full, clear, and exact description, reference being had to the accompanying drawings, making part of this specification, in which—

Figure 1 is a plan of a turbine water-wheel, with my improvements applied thereto.

Figure 2 is a horizontal section, representing the gates half open.

Figure 3 is a detail, in vertical section, on the line $z z$ of fig. 1, representing the gate half open.

Figure 4 is a horizontal section, representing the gates wholly open.

Figure 5 is a horizontal section, representing the gates closed.

My invention consists in two annular shells or casings, each provided with a series of scrolls, and placed outside the wheel, one casing being moved around or within the other, which is stationary, so that when the gate is thereby opened to its full width, the line of each scroll of the outer casing and that of the adjacent scroll of the inner casing, will form one and the same continuous scroll, extending from one inlet-opening to or nearly to the next opening, by which construction and arrangement, the passages of the water to the wheel may be contracted to a greater or less degree, and the water impinge upon every point in the circumference of the wheel, and a large percentage of the power utilized either when the gate is wholly or partially opened.

To enable others skilled in the art to understand my invention, I will proceed to describe the manner in which I have carried it out.

In the said drawings—

A is a horizontal wheel, provided with buckets a .

B is the vertical shaft of the said wheel, having its bearing in a step, formed in a bar, C, extended diametrically across the inner shell or casing D, which is of a circular form, in horizontal section, and snugly encloses the wheel A.

This inner casing is stationary, and is provided with a series of openings, b , for the passage of the water from the flume to the wheel.

A series of curved surfaces or scrolls, c , corresponding in number to the inlet-openings b , is formed on the inside of the inner casing D, between its upper rim or flange 6 and its lower flange 7.

Each scroll c extends from the inside to the outside of the flanges 6 7.

E is the outer shell or casing, which fits snugly

upon and is moved around the outside of the inner casing by the toothed wheel G, engaging with a rack, H, the top of the inner casing being provided with a cap-plate, I, in bearings in which the shaft of the toothed wheel G revolves.

The outer shell or casing E is also provided with a series of openings d and e , of corresponding form and number as the inner casing D.

When the outer casing E is moved around so as to fully open the inlet-passages, the line of the inside of the inner casing and the adjacent line of the inside of the outer casing a , forming the outside of each inlet-passage, unite and form nearly or exactly one and the same continuous curve or scroll, extending from one inlet opening to or nearly to the next inlet-opening, (see fig. 4,) while the outside, 8, of the guiding-curve of the outer casing, and the outside of the guiding-curve of the inner casing, form the inside of an unobstructed curved inlet-passage, thus insuring the unimpeded action of the water on all points of the circumference simultaneously.

When the inlet-passages or gates are half-way open, the outside of the inner casing forms, as above described, a portion of the inside of the passages, thus securing a more uniform pressure on the wheel.

The inlet-passages may all be gradually contracted simultaneously, and a large percentage of the power of the water utilized, whether the gate be wholly or partially open.

Instead of the construction above described, the inner casing may be movable within an outer stationary casing, without departing from the spirit of my invention.

Claims.

What I claim as my invention, and desire to secure by Letters Patent, is—

An inner and an outer casing, so constructed and arranged, that when the inlet-passages are fully open, the line of the inside of the inner casing and the adjacent line of the inside of the outside casing form nearly or exactly one and the same extended curved line, substantially as and for the purpose set forth.

Also, in combination with the above, an unobstructed inlet-passage, the inside of which is formed by the union of the adjacent outside lines of the guiding-curves of the inner and outer casings, substantially as and for the purpose set forth.

ALONZO WARREN.
